UNITED STATES PATENT OFFICE.

EMIL HELD, OF NEW YORK, N. Y., ASSIGNOR TO HIMSELF AND RUDOLPH IPPICH, OF SAME PLACE.

DESIGN FOR CHENILLE.

SPECIFICATION forming part of Design No. 16,212, dated August 25, 1885.

Application filed June 19, 1885. Term of patent 7 years.

To all whom it may concern:

Be it known that I, EMIL HELD, a citizen of Germany, residing at New York, in the county and State of New York, have invented and produced a new and original Design for Chenille, of which the following is a specification, reference being had to the accompanying drawing, forming part thereof.

The drawing represents a side view of a length of my newly-designed chenille.

This invention relates to a new design for chenille; and it consists in a series of alternating wider and narrower parts or sections, *a*. Each section presents the appearance of spiral 15 strips of tuft-like or open fabric, *c*, alternating with spiral strips of loop-like or closed fabric, *d*, as shown, these strips being flush with each other and presenting an even surface.

The characteristic feature of the design consists of alternating wider and narrower sections, each section presenting the appearance of alternating spiral tuft-like and spiral loop-like strips. 20

I claim—

The design for chenille, having alternating wider sections *a* and narrower sections *b*, each section presenting the appearance of a tuft-like spiral strip, *c*, alternating with a loop-like spiral strip, *d*, these strips being flush with each other and presenting an even surface, substantially as shown. 25 30

EMIL HELD.
